UNITED STATES PATENT OFFICE.

LOUIS HEIDT, OF BROOKLYN, NEW YORK.

DESIGN FOR A GLASS SHEET OR PANE.

SPECIFICATION forming part of Design No. 15,972, dated March 17, 1885.

Application filed October 16, 1884. Term of patent 3½ years.

To all whom it may concern:

Be it known that I, LOUIS HEIDT, a citizen of the United States, residing in the city of Brooklyn, county of Kings, and State of New York, have invented and produced a new and original Design in Glass Sheets or Panes, of which the following is a specification, reference being had to the accompanying drawing, forming a part hereof.

10 The figure is a view of my design for sheets or panes of glass.

A A are the irregular inclosures; a a, the veins; b b, the pyramidal projections.

15 My design consists, essentially, of a series of small irregular pyramidal projections rising in low relief above the general surface of the pane. These pyramids, whose facets are irregular, are also irregularly grouped together, and are separated into small aggregations by 20 regular vein-like lines intersecting, so as to form irregular or what might be termed "shapeless" figures.

The veins may be depressed in the form of

channels, or may consist of small corrugations, the effect in either case being almost the same. 25

The number of facets of the pyramids may vary without altering the general appearance of the design, and the design may be produced upon either one or both surfaces of the pane and in any color desired.

30 In the drawing only a portion of the veined inclosures are shown filled with the pyramidal projections; but it is intended to fill all of them in this way.

I claim—

35 The design for a glass pane or sheet, consisting of a large number of small pyramidal projections in low relief irregularly grouped together within irregular inclosures formed by intersecting veins, which are either depressions or corrugations, all substantially as shown and described.

LOUIS HEIDT.
